UNITED STATES PATENT OFFICE.

JAMES F. WELCH, OF BROOKLYN, NEW YORK, ASSIGNOR TO THE GLEN COVE MACHINE COMPANY, (LIMITED,) OF SAME PLACE.

WOOD-PLANING MACHINE.

SPECIFICATION forming part of Letters Patent No. 390,829, dated October 9, 1888.

Application filed December 9, 1887. Serial No. 237,396. (No model.)

To all whom it may concern:

Be it known that I, JAMES F. WELCH, of Brooklyn, (Green Point,) in the county of Kings and State of New York, have invented a new and useful Improvement in Wood-Planing Machines, of which the following is a specification.

Modern wood-planing machines have been brought to such a state of perfection in regard to rapid feeding that with machines of the usual construction there can be little or no further advance in that direction, because as the speed of the feed increases beyond a certain point the quality of the work deteriorates. It is therefore very desirable to produce a machine in which the lumber can be fed moderately fast to the cutter, and which will yet deliver a large quantity of the very best work; and the object of my invention is to provide such a machine which, comprising two feed-ways for lumber, arranged one above the other and each provided with the cutter-heads and appurtenances for performing simultaneously upon two levels similar operations upon two different pieces of lumber, is capable of doing double the amount of work that can be done with the machines now in common use, and of as good quality.

The invention is more particularly, though not exclusively, intended to be embodied in machines for planing comparatively thin stuff—such, for example, as flooring and ceiling—where the variations in thickness which must be accommodated by the feed-rolls will be comparatively slight.

The invention will be hereinafter described, and then pointed out in the claims.

In the accompanying drawings, Figure 1 is a side elevation of a planing-machine embodying my invention. Fig. 1* is a detail view illustrating connections whereby the weights are applied for acting upon the movable journal-boxes of the upper feed-rolls; and Fig. 1** is a similar detailed view of the connections whereby weight is applied to the screws which control the upper roll-boxes of the lower set of rolls. Fig. 2 is a plan of the machine. Fig. 3 is a longitudinal section of the machine. Fig. 4 is a transverse section of the machine upon the dotted line $x x$, Fig. 1. Figs. 5 and 6 are

detailed views upon a larger scale, illustrating the gearing whereby the boxes of the upper feed-rolls are raised and lowered; and Fig. 7 is a vertical section of one of the side cutter-heads and head-plates, including a portion of 55 the spindle and showing how the cutter-head may be accurately adjusted to height lengthwise of the spindle.

Similar letters of reference designate corresponding parts in all the figures.

As here represented, the machine comprises two upper cutter-heads, A A', two pairs of side cutter-heads, B B', and two lower cutter-heads, C C'; but the cutter-heads for performing any one of the three operations may be 65 omitted, if desired, without departing from my invention—that is to say, the machine may comprise only the upper cutter-heads, A A', or, in addition thereto, the side cutter-heads, B B'; or the machine may have both the lower 7c cutter-heads, C C', and the upper cutter-heads, A A', or the side cutter-heads, B B'. Each of the several cutter-heads has employed in connection with it the several appliances which are employed in ordinary wood-planing machines, and which need no extended description.

With the upper cutter-heads, A A', are employed a chip-breaker, a' , and a presser-bar, a , on the opposite side of the cutter-head, and 80 the cutter-head boxes a^2 may be adjusted upward and downward along the posts d by screws a^3 , the screws for the boxes on opposite sides of the machine being geared together by a cross-shaft, a^4 , as is usual.

In connection with each of the upper cutter-heads, A A', is a bed, E or E', and upon the same levels as the two beds E E', one above another, are the lower and upper feedways, F F', which at the carrying-in end of the machine are prolonged in the form of gratings f f' , as shown in Fig. 3, and which are provided with the usual side guides, G² G³. The lower and upper side cutter-heads, B B', are secured upon a side cutter-spindle, B², common to 95 both of them, and said cutter-heads work upon head-plates B³ B⁴, which are upon the same level as the feedways F F'. Upon each head-plate is a chip breaker, b , for operating in connection therewith, and such chip-breakers 100

may be supported and moved in a direction toward the lumber, so as to hold them tightly pressed against the lumber by weights applied through suitable connections, as is shown and 5 described in the patent to Gray & Hutchinson, No. 315,406, granted April 7, 1885. The upper side cutter-head, B', may be adjusted vertically upon its spindle B², so as to bring it to exact height relative to the feedway F' by 10 means of a set-screw, b', bearing against the end of the spindle, and the lower side cutter-head, B, may be similarly adjusted as to height by means of a set-screw, b², inserted through the cutter-head and bearing against a collar, 15 b³, upon the spindle, as is represented in Fig. 7. Each of the lower cutter-heads, C C', operates in connection with bars or mouth-pieces C² C³, upon opposite sides thereof, and over 20 which the lumber passes as it is fed through the two feedways F F', and above each lower cutter-head is a top presser, C⁴, serving to hold the lumber down and prevent its rising when acted upon by the cutters. Each top presser, C⁴, is adjustable vertically toward and from 25 its cutter-head in a suitable movable cross-frame, C⁵, and the mouth-pieces or bars C² C³ and the top presser, C⁴, may be supported and adjusted as described and shown in the patent to Welch, Hutchinson & Gray, No. 324,056, 30 dated August 15, 1885.

Beyond the outer bar or mouth-piece, C², for each lower cutter-head, C C', is a delivery-table, C⁶ C⁷, over which the lumber passes. The delivery-table C⁶ for the lower cutter-head, C, may be supported by arms c, which 35 extend downward and are pivoted at c' to the frame D of the machine, as shown in Fig. 3, and the bar or mouth-piece C² pertaining to the lower cutter-head, C, may be also supported by the downwardly-extending arms c.

The delivery-table C⁷, for the lower cutter-head C', which is upon the upper level, may be supported, as shown in Figs. 1 and 3, upon the top of the frame C⁵, pertaining to the lower 45 cutter-head C, which is upon the lower level. For feeding lumber through the lower feedway, F, and to be operated upon by the knives of the upper cutter-head, A, the side cutter-heads, B, and the lower cutter-head C, I may 50 employ pairs of feed-rolls G G', and for similarly feeding lumber through the upper feedway, F', to be operated upon by the knives of the upper cutter-head, A', the side cutter-heads, B', and the lower cutter-head C', I employ 55 other similar pairs of feeding-rolls, H H'. I have here represented three pairs of feed-rolls, G G', in the lower set, and also three pairs of feed-rolls, H H', in the upper set, and the pairs of rolls in the lower set are separated 60 from each other sufficiently, so that the lower rolls, H, of the upper set are arranged between the upper rolls, G', of the lower set. This enables the upper feedway, F', to be arranged at a considerably lower level than it 65 would be if the rolls of the upper set were arranged with the full diameter of the lower rolls,

H, above the upper rolls, G', of the lower set. I have represented the feed-rolls of both sets as driven from the usual pinion-shaft, I. The two rolls of each pair are geared together by wheels 70 g, and the wheels g upon the upper feed-rolls, G', of the lower set each engage with a corresponding wheel, g, upon the lower roll, H, of the upper set, which is arranged immediately behind. As the variations in the thickness of 75 lumber to be planed by a machine of this character will ordinarily be but slight, expansion-gears for each pair of feed-rolls will seldom be necessary, as is usual in wood-planing machines, but the upper roll, G' or H', of each 80 pair is fitted to turn in vertically-movable boxes h, while the lower roll, G or H, of each pair is fitted to turn in stationary boxes h'. The upper roll-boxes, h, of each pair have a sliding movement or adjustment to a limited 85 extent, and the gear-wheels g should have their teeth so constructed or of such contour that they will drive properly, notwithstanding the vertical adjustment of the upper feed-rolls, G', of the lower set, but expansion-gears of the 90 usual character may be used when necessary.

Upon the pinion-shaft I is a feed-pinion, i, gearing into a wheel, i', which is also in engagement with a larger wheel, i², upon the lower feed-roll, G, of the pair nearest the cutter-head, and the feed-rolls which are back of that point are arranged to be driven by providing a similar wheel, i², upon each of the lower feed-rolls, G, and gearing the wheels i² with each other by other intermediate wheels 95 or pinions, i'.

The boxes h of the adjustable upper rolls, G', are fitted to slide upon guides on the roll-stands H², and have connected with them vertical adjusting-screws J J', the former serving 105 to adjust the boxes of the upper feed-rolls, G', and the latter to adjust the boxes of the upper feed-rolls, H', one for each pair. It is advantageous to adjust all the upper feed-rolls of both sets simultaneously, and I have here represented two adjusting-shafts, J² J³, which are geared together by wheels j, as shown in Figs. 1, 5, and 6, so that a handle or hand-crank applied to either shaft will serve to turn both of them. The shaft J² is provided with worms 110 j', which engage with worm-wheels j² on the several screws J, and the shaft J³ is similarly provided with worms or screws j³, which engage with worm-wheels j⁴ on the several screws J'. The worm-and-screw gearing for connecting the two shafts J² J³ with the screws J J' is shown in detail in Figs. 5 and 6, and, as shown 115 in Fig. 5, the upper ends of the screws J J' are fitted to bearings j⁵, which permit the upward movement of said screws in the bearings, 120 but said screws are provided with collars j⁶, which prevent the downward movement of the screws below a certain limit.

As in other wood-planing machines, the upper rolls, G' H', of both sets are weighted, so 125 as to permit them to rise as the lumber passes under them and to cause them to still exert a

sufficient bite upon the lumber to feed it along by their rotation. The means for weighting the said upper rolls is shown by dotted lines in Fig. 1 and by full lines in Fig. 1*. As before described, the roll-adjusting screws $J J'$ are in threaded engagement with the adjustable roll-boxes h of the upper rolls.

As best shown in Figs. 1* and 1**, the screws J have applied to them swivels j^1 , which are pivotally connected with beams J^4 , and with the two beams J^4 is pivotally connected at the points j^1 a third beam or bar, J^5 , from which depends a stirrup, J^6 , in which hangs or on which bears the weighted lever J^7 . As is shown in Fig. 1, the lever J^7 has applied to it an adjustable weight, j^9 , and is fulcrumed at j^{10} . By the beams J^4 and J^5 , connected as best shown in Fig. 1**¹, the weighted lever J^7 is applied to the screws J , which control the upper roll-boxes of the lower set. The swivels j^1 , which are applied to the lower ends of the adjusting-screws J' , are pivotally connected with two beams, J^8 , and with the two beams J^8 is pivotally connected at the points j^{12} a third beam or bar, J^9 , from which depends a stirrup, J^{10} , in which hangs the weighted lever J^{11} . By the beams J^8 J^9 , constructed as shown in Fig. 1*, the weighted lever J^{11} is applied to screws J' , which control the upper roll-boxes of the upper set of rolls.

As shown in Fig. 1, the lever J^{11} has applied to it an adjustable weight, j^9 , and is fulcrumed at j^{10} . It will be understood that the swivels j^1 j^{11} , which are applied to the screws $J J'$ of the middle pair, are respectively connected, the first, j^1 , with both beams or bars J^4 of that pair, and the second, j^{11} , with both beams or bars J^8 of the second pair. By this system of connections the upper rolls of all the pairs of both sets are properly weighted, and at the same time freedom is afforded for the upper roll of any one pair to lift independently of the upper rolls of the other pairs of that set.

According to the above-described gearing for driving the feed-rolls, it will be observed that all the power required to drive all the rolls is transmitted from the shaft I , through the pinion i , wheel i' , and through the lower feed-roll, G , of the first pair, which is adjacent to the cutter-heads. In order to distribute the power necessary to drive the feed-rolls through the lower rolls, G , of the several pairs comprised in the lower set, I may employ a modified arrangement of gearing. (Shown in Fig. 3 entirely by dotted lines.) The feed-pinion i and its shaft I may be arranged considerably behind the position shown by full lines, and said pinion may be geared with two large wheels, i^2 . Concentric with these large wheels are small pinions i^4 , one engaging with the wheel i^2 upon the lower feed-roll, G , of the pair which is nearest the feeding end of the machine, and the other pinion, i^4 , engaging with the wheels i^2 on the lower feed-rolls, G , of the second and third pairs from the feeding end of the machine. Either arrangement of feed-gearing for imparting motion to the wheels

i^2 upon the lower feed-rolls, G , may be employed, according to which shall prove in practice to be the most desirable.

It will be seen that by my invention I provide, where certain kinds of lumber are to be planed, for doing double the amount of work that can be done upon a machine having but a single set of feed-rolls and but one feedway, and the cost of this machine and also the power to drive it is far less than the cost of two ordinary planing-machines and the power to drive them. It will be observed that the adjusting-screws $J J'$ are on one side only of the machine, but each pair of upper roll-boxes, h , are connected by rods o with arms o' upon a common rock-shaft, o^2 , and are by such connection caused to rise and fall simultaneously.

What I claim as my invention, and desire to secure by Letters Patent, is—

1. The combination, in a wood planing machine, of two cutter-heads supported one above the other and feedways for lumber one above the other at levels corresponding with the levels of the two cutter-heads, two sets of feed-rolls, one for each of said feedways, and a main framing common to and serving to support all of said parts, substantially as herein described.

2. The combination, in a wood planing machine, of two cutter-heads supported upon different levels, two feedways for lumber at correspondingly-different levels, for presenting lumber to said cutter-heads, and two sets of feed-rolls, the lower rolls of the upper set being arranged between the upper rolls of the lower set, substantially as herein described.

3. The combination, in a wood-planing machine, of cutter-heads supported upon different levels, two feedways for lumber at correspondingly-different levels, two sets of feed-rolls, the lower rolls of the upper set being arranged between the upper rolls of the lower set, and gear-wheels, whereby the rolls of each pair are geared together, and whereby the upper roll of each pair of the lower set is geared with the lower roll of the adjacent pair of the upper set, substantially as herein described.

4. In a wood-planing machine, the combination, with two cutter-heads supported at different levels, and two feedways at correspondingly-different levels, of two side cutter-heads at the levels of the feedways, and a side cutter-spindle common to both cutter-heads, and to which they are secured one above another, and two sets of feed-rolls for feeding lumber to the two cutter-heads, substantially as herein described.

5. In a wood-planing machine, the combination, with two cutter-heads operating at different levels and two feedways at correspondingly-different levels, of two sets of feed-rolls, the upper rolls of the several pairs being mounted in sliding boxes, and gearing whereby the boxes of the upper rolls of all the pairs in both sets may be raised and lowered simultaneously, substantially as herein described.

6. In a wood-planing machine, the combi-

nation, with two lower cutter-heads arranged at different levels, and the cutter-head at the lower level being at the delivery end of the machine, and two feedways for lumber at correspondingly-different levels, of upper pressers for both cutter-heads, a delivery-table for the upper run of lumber supported on the presser-frame of the lower cutter-head at the lower

level, and two sets of feed-rolls for feeding lumber to the two cutter-heads simultaneously, to substantially as herein described.

JAMES F. WELCH.
